UNITED STATES PATENT OFFICE.

CHARLES F. HANINGTON, OF NEW YORK, N. Y., ASSIGNOR TO THE
MECHANICAL DOOR HINGE CHECK COMPANY, OF SAME PLACE.

DOOR-CHECK.

SPECIFICATION forming part of Letters Patent No. 629,248, dated July 18, 1899.

Application filed October 28, 1898. Serial No. 694,786. (No model.)

To all whom it may concern:

Be it known that I, CHARLES F. HANINGTON, a citizen of the United States, residing in the borough of Manhattan, in the city, county, and State of New York, have invented certain new and useful Improvements in Mechanical Door-Checks, of which the following is a specification.

My invention relates to various new and useful improvements in mechanical door-checks; and the object of the invention is to simplify the construction and improve the operation of such devices.

In carrying out my invention I provide a hinge of any suitable type having two leaves and a barrel and combine therewith mechanical checking devices which will be simple in construction, effective in operation, durable in use, capable of being easily reached for purposes of repair, and wherein when desired the checking action may be discontinued.

The type of device to which my invention particularly relates is that shown and described in my application for Letters Patent filed October 19, 1898, Serial No. 693,980, and the present improvements are designed to simplify the construction and improve the operation of that device. The present invention covers only specific improvements on the device claimed in said application, and so much of the invention of said application as is necessary for a complete understanding of the present improvements is described, but not claimed herein.

In order that my invention may be better understood, attention is directed to the accompanying drawings, forming part of this specification, and in which—

Figure 1 is a side elevation, partly in section, of an ordinary door-hinge equipped with my present invention, the hinge being represented in a closed position; Fig. 2, a similar view showing the two leaves separated at an angle of ninety degrees; Fig. 3, a horizontal sectional view on the line 3-3 of Fig. 1, showing the position of the hinge when the door is entirely open; and Fig. 4, a view similar to Fig. 3, illustrating the position of the parts when the hinge has been closed to the checking position.

In all of the above views corresponding parts are represented by the same numerals of reference.

1 is a hinge-barrel, and 2 3 are the two leaves. One of such leaves is secured to the frame of the door way or jamb and the other leaf is secured to the door. In the drawings I illustrate the barrel 1 as being carried by the leaf 3, and I illustrate the leaf 2 as being pivoted on the ordinary pintle 3', which is mounted in said barrel. Carried by the barrel is the sleeve 4, in which is formed a slot 5, at the end of which slot is a shoulder 6, upon which is imposed the checking thrust or strain. The collar 4 is secured to the pintle or barrel in any suitable way, as by screws 7. Extending parallel with the slot 5, above the shoulder 6, is a shorter slot 8, which communicates with the slot 5 and is provided above and in front of the shoulder 6 with a curved cam-surface 9. It will be understood that instead of providing a collar secured to the pintle or barrel, said collar carrying a shoulder 6 and a cam-surface 9, it will be possible to make use of a separate shoulder 6 and a separate cam-surface 9, secured independently to the pintle or barrel, as I have described in my said application. Adapted to work in the slots 5 and 8 is a checking-pawl 10, which in this instance is carried on the leaf 2, within a recess 11 in said leaf and upon a sufficiently heavy screw 12. Secured to the leaf 2 and in engagement with the checking-pawl 10 is a checking-spring 13, which in this instance is a leaf-spring secured to said leaf by the screws 14 and 15, the latter working in a slotted opening 17, so as to allow for slight movement of said spring when the latter is bowed at its center. The checking-pawl 10 is capable of movement within the recess 11 and parallel with the spring 13. Said checking-pawl is also capable of movement outward from the hinge-leaf 2 against the tension of the spring 13, to allow of which movement the said checking-pawl 10 is somewhat loosely mounted on the pivot 12, as will be understood.

So far as I have described my improved door-check the parts correspond with the hinge described in my said application. Instead of employing a leaf-spring for the pur-

pose of elevating the checking-pawl 10 after the same has been tripped, as will be explained, I prefer to make use of a spiral spring 18, located in a recess 19 in the hinge-leaf 2 and mounted between lugs 20 21, formed on said leaf and the checking-pawl, respectively. The recess 19 is made preferably V-shaped, so as to allow for the swinging movement of the spring 18 in expanding when the pawl 10 is moved upward. I find that by employing a spiral spring for moving this pawl the device will be much more certain in its operation than when a leaf-spring is used. Instead of employing a locking-dog carried by the checking-pawl, as I have described in my application, I prefer to make use of a separate small locking-dog pivoted to the hinge-leaf 2, as in this way I am not required to weaken the checking-pawl in any way, and the device will be somewhat simplified. This locking-dog 22 is preferably mounted in a kerf or slot 23, formed in the leaf 2, and is pivoted on a stud 24, mounted on a small lug 25, cast with said leaf or secured thereto. The said locking-dog is provided with a latch-head 26, which preferably engages over the upper surface of the checking-pawl to hold said checking-pawl normally in a depressed position. Obviously the said latch-head of the locking-dog may engage with a recess formed on the inner surface of said checking-pawl instead of above the latter. The inner end of the locking-dog projects within the barrel 1 and is adapted to be struck at the proper moment to release the latch-head thereof from the checking-pawl and allow the latter to be moved upward by the spring 18. In order to keep the latch-head of the locking-dog normally in engagement with the checking-pawl to lock the latter downward, I prefer to make use of a leaf-spring 27, pivoted to the leaf 2 and adapted to engage with the locking-dog on either side of its pivot. In this way the spring 27 may be employed to keep the locking-dog in a normally-locked or in a normally-unlocked position, for reasons which I will explain. In order to trip the locking-dog at the proper moment, I make use of a supplemental shoulder 28, formed in the collar 4 and so located relatively to the shoulder 6 that the free end of the locking-dog will be engaged thereby an instant before said shoulder strikes the end of the checking-pawl.

The operation of the device is as follows: Normally the inner end of the checking-pawl 10 will work in the slot 5, the said pawl being locked in a depressed position against the tension of the spring 18 by the engagement of the latch-head 26 with the said checking-pawl. When the door is closed by hand or by a suitable spring device, the two leaves 2 and 3 will be moved almost together, so as to first engage the auxiliary shoulder 28 with the free end of the locking-dog to disengage the latch-head thereof from the checking-pawl. Before the spring 18 can force the checking-pawl 10 upward into the slot 8 the rear end

of the checking-pawl 10 will have been engaged by the shoulder 6, and the friction thus produced between these parts will prevent upward movement of the pawl. This engagement between the inner end of the checking-pawl and the shoulder 6 takes place immediately before the door is closed, and the strain will be thus thrown upon the checking-spring 18, which will be caused to buckle outward at its center under the slight movement of the checking-pawl against the spring. An elastic checking action is thus secured. During this checking operation the auxiliary shoulder 28 is still in engagement with the free end of the locking-dog and has simply moved the latter on its pivot against the tension of the spring 27. If necessary, the leaf 3 may be cut away at 29 to accommodate this movement of the locking-dog. When the door has rebounded, the inner end of the checking-pawl 10 will be disengaged from the shoulder 6 to relieve the friction between the two, and the spring 18 will thus immediately elevate the said pawl and cause its inner end to work in the slot 8 to thus allow the leaves to engage together, as shown in Fig. 1, and to permit the door to close. When the door is reopened, the inner end of the checking-pawl will engage the cam-surface 9, and said pawl will be moved downward into the slot 5. Immediately thereafter the latch-head of the locking-dog will engage over the checking-pawl 10 to hold the latter in its depressed normal position. When it is desired that the checking action should not take place, the leaf-spring 27 is moved across the pivot 24 of the locking-dog, so as to hold the free end thereof normally depressed and to thereby retract the locking-head from engagement with the checking-pawl. When this is done, it will be seen that when the door closes there will be no engagement between the pawl 10 and the shoulder 6, since the spring 18 will have elevated the pawl into line with the slot 8 before such engagement can take place.

Having now described my invention, what I claim as new, and desire to secure by Letters Patent, is as follows:

1. In a door-check, the combination of the stationary and movable hinge-leaves, a barrel carried by the movable leaf, a shoulder movable with said barrel, a checking-pawl carried by the stationary leaf and adapted to be engaged by said shoulder before the door is closed, said checking-pawl being movable with respect to its leaf in a plane parallel with the closing movement, a spring for resisting said movement, whereby an elastic checking action will take place, means for locking the pawl normally in the plane of said shoulder, and a spiral spring located in a V-shaped recess in the stationary leaf, engaging said checking-pawl and tending to move the same out of the plane of said shoulder, substantially as set forth.

2. In a door-check, the combination of the two hinge-leaves, one of which carries a bar-

- rel, a shoulder connected to one leaf, a checking-pawl carried by the other leaf and adapted to engage said shoulder before the door is closed, a checking-spring for receiving the impact of the engagement between said shoulder and pawl, and a locking-dog carried by the leaf and normally locking said pawl in a position to engage the shoulder, substantially as set forth.
- 10 3. In a door-check, the combination of the two hinge-leaves, one of which carries a barrel, a shoulder connected to one leaf, a checking-pawl carried by the other leaf and adapted to engage said shoulder before the door is closed, a checking-spring for receiving the impact of the engagement between said shoulder and pawl, a locking-dog carried by the leaf and normally locking said pawl in a position to engage the shoulder, and means for
- 15 releasing said locking-dog when the pawl engages the shoulder, whereby upon the rebound the pawl will be moved out of its engagement with the shoulder to allow the closing of the door, substantially as set forth.
- 20 4. In a door-check, the combination of the two hinge-leaves, one of which carries a barrel, a shoulder connected to one leaf, a checking-pawl carried by the other leaf and adapted to engage said shoulder before the door is closed, a checking-spring for receiving the impact of the engagement between said shoulder and pawl, a locking-dog carried by the leaf and normally locking said pawl in a position to engage the shoulder, means for re-
- 25 leasing said locking-dog when the pawl engages the shoulder, whereby upon the rebound the pawl will be moved out of its engagement with the shoulder to allow the clos-
- ing of the door, and means for automatically resetting the pawl and for resetting the locking-dog, substantially as set forth.
- 30 5. In a door-check, the combination of the two hinge-leaves, one of which carries a barrel, a shoulder connected to one leaf, a checking-pawl carried by the other leaf and adapted to engage said shoulder before the door is closed, a checking-spring for receiving the impact of the engagement between said shoulder and pawl, a locking-dog carried by the leaf and normally locking said pawl in a position to engage the shoulder, and an auxiliary or supplemental shoulder for releasing said locking-dog when the pawl engages the shoulder, whereby upon the rebound the pawl will be moved out of its engagement with the shoulder to allow the closing of the door, substantially as set forth.
- 35 6. In a door-check, the combination of the two hinge-leaves, one of which carries a barrel, a shoulder connected to one leaf, a checking-pawl carried by the other leaf and adapted to engage said shoulder before the door is closed, a checking-spring for receiving the impact of the engagement between said shoulder and pawl, a locking-dog carried by said leaf and normally locking said pawl in a position to engage the shoulder, and a spring for maintaining said locking-dog in either a normally locked or unlocked position, substantially as set forth.

This specification signed and witnessed this
25th day of October, 1898.
